UNITED STATES PATENT OFFICE

165,916

COOKING UTENSIL COVER

John C. Hampshire, New Haven, Conn., assignor to Bridgeport Brass Company, Bridgeport,
Conn., a corporation of Connecticut

Application July 26, 1950, Serial No. 11,406

Term of patent 14 years

(Cl. D44—29)

To all whom it may concern:

Be it known that I, John C. Hampshire, a citizen of the Dominion of Canada and a resident of New Haven, New Haven County, State of Connecticut, have invented a new, original, and ornamental Design for a Cooking Utensil Cover, of which the following is a specification, reference being had to the accompanying drawing, forming a part hereof.

Fig. 1 is a side elevational view of a cooking utensil cover showing my new design;

Fig. 2 is a top plan view of the handle;

Fig. 3 is a side elevational view; and

Fig. 4 is a cross-sectional view thereof taken on line 4—4 of Fig. 3.

The dominant features of my design reside in the portions shown in full lines.

I claim:

The ornamental design for a cooking utensil cover, substantially as shown and described.

JOHN C. HAMPSHIRE.
